GARMENT STRIPPING MACHINE

Irving Primus, Forest Hills, N. Y., assignor to
Isidor Gerber, Brooklyn, N. Y.

Application January 4, 1946, Serial No. 639,025

7 Claims. (Cl. 223—78)

1

This invention relates to garment pressing machines and particularly to the mechanism therein for stripping a glove or the like garment from a form on which the garment has been mounted for pressing or stretching purposes.

The invention contemplates the provision of yieldable stripping means self-adjusting to variations in the thicknesses, shapes and positions of the garments fed to said means, to press directly without slipping upon both sides of the garment (hereinafter referred to as a glove), and to move longitudinally or in the stripping direction while engaging the glove thereby to strip it from the form without the aid of belts, rolls or the like.

The invention further contemplates the provision of yieldable means adapted to be clamped frictionally upon a glove mounted on a form, and moved with the glove a sufficient distance to strip the glove off the form, said means holding the glove flat during the stripping operation and releasing the glove after it has been completely stripped.

The various objects of the invention will be clear from the description which follows and from the drawings, in which

Fig. 1 is a top plan view of the stripping mechanism in the inoperative position thereof, the clamping plates being shown separated ready to receive the form therebetween.

Fig. 2 is a similar view of the clamping levers and plates in the stripping positions thereof and showing the link for limiting the separating movement of the plates.

Fig. 3 is a front elevational view of the stripping mechanism.

Fig. 4 is a side elevational view thereof.

In the practical embodiment of the invention shown by way of example, the form 10, having mounted thereon the glove or other garment 11, is swung by any suitable mechanism such as is shown for example in my copending application for Garment stretching and pressing machine, Serial No. 638,073, between the two rows of clamping plates 12 and 13 (Fig. 4). Each plate is preferably, though not necessarily, in the form of a disc having a knurled or roughened inner face intended to engage the glove frictionally and without slipping. Extending axially from the disc is the support rod 14, slidably mounted in one of the levers 15 or 16, and carrying the compression spring 17 which urges the plate inwardly toward the corresponding plate of the other row. A collar 18 is fixed to the rod 14, and by its engagement with the lever, limits the extent of the

2

inward movement of the rod and of the plate thereon.

Each of the levers is swung toward the form 10 at the proper time, and while the form is at rest, to clamp the form and the garment thereon between the rows of plates 12 and 13. For this purpose, the lever 15 is pivoted as at 19 and the lever 16 is similarly pivoted at 20 to the upper lugs 21 projecting transversely from the vertically reciprocating slide 22. The spring 23 joining the left hand ends of the levers (as viewed in Figs. 1 and 2), urges the levers into the positions thereof shown in Fig. 1 and thereby urges the rollers 24 at the right hand ends of the respective levers into engagement with the corresponding upright cam plate 25, which serves as a fixed cam to swing the lever about its pivot into the position shown in Fig. 2. The cam plate 25 is secured to the frame 26 of the machine as by means of the bracket 27 and is of the proper length to maintain the plates 12 and 13 in their clamping and stripping positions until the glove is completely stripped from the form. Preferably, the plate 25 is bent laterally at its lower end to permit the spring 23 to swing the levers 15 and 16 and the clamping plates carried thereby outwardly at the proper time to release the glove from the clamping plates.

When so released, the glove drops on to the curved guide member 28 suitably secured to the frame member 26 as by the bracket member 30, said guide member being suitably curved to direct the glove toward the belt 31. The glove when released falls along the member 28, lying flat thereon, and drops in a flat position on to the belt 31, which carries the glove out of the machine.

To limit the extent of the movement of the plates 12 and 13, the link 32 (Fig. 2) is secured to the levers 15 and 16 adjacent the spring 23, slots as 33, 34 being provided at the respective ends of the link. Passing through each of the slots and fixed to each lever is a pin 35 which may move in the slot through which it projects, from one end of the slot to the other end thereof. When the pins are at the outer ends of the slots, further inward movement of the levers is prevented, and similarly, when the pins are at the inner ends of the slots, the levers and the plates thereon cannot be further separated.

In addition to the inward and outward movements of said levers and of the clamping plates alternately to grip and to release the glove, said levers and plates are also reciprocated vertically by means which will now be described. The slide 22 on which the levers are pivotally mounted is

provided with a T-shaped projection or guide 36 reciprocating in the vertical T-shaped slot or groove 37 provided between the spaced apart gib members 38 and 39 which are secured to the arm 40 of the frame member 26. For reciprocating the slide in the groove 37, the connecting link 41 is pivotally secured at its lower end to the lug 42 extending from the lower end of the slide 22, the link being pivotally secured at its upper end to the crank 43 fixed to the shaft 44, said shaft being rotatably mounted in the frame member 26. It will be seen that when the shaft is rotated, consequent rotation of the crank causes reciprocation of the slide and of the levers and clamping plates as a unit.

Since the cam rollers 24 are preferably free to ride off the fixed cam plates 25 controlling the inward and outward movement thereof, at the time when said rollers approach the ends of upward reciprocatory strokes thereof, means are provided to carry the rollers back on to the cam plates as the descent of the slide is begun. It should be noted that the rollers ride off the cam plates for the purpose of insuring maximum separation of the clamping plates 12 and 13 for the proper entrance therebetween of the form 10 which may vary considerably in size for different gloves. As best seen in Fig. 4, the means for carrying the cam rollers back on to the operative inner surfaces 45 of the cam plates 25 comprises yieldable guide members each in the form of an adjustable plate cam 46 and each pivoted as by means of a hinge 47 to the plate cam 25 at a point out of the vertical path of movement of the cam rollers. A leaf spring as 48 secured to the plate cam 25, is provided with a suitably bent upper end part engaging the hinged plate cam 46 and urging said cam against the stop 49. The stop is threadedly engaged by the adjusting nut 50 thereon and is adjustable to determine the angular position which the cam plate 46 may assume, it being understood that the upper end of the plate 46 is arranged outwardly beyond the roller 24 so that said roller on its descent engages the inner face of the guiding cam plate 46 and is forced inwardly thereby into position to ride on to the inner surface 45 of the plate 25. Preferably, the angle of the plate 46 to the vertical is about the same as that of the lower end or tip of the form.

Said plate 25 is so arranged as to maintain the lever 15 or 16 in its innermost position during the descent thereof, in which position the levers compress the springs 17 and force the clamping plates 12 and 13 inwardly into yieldable but pressed contact with the end portion of the partly stripped glove. To initiate the stripping operation, the guide cam plate 46 first swings the levers 15 and 16 sufficiently to clamp the glove and the form 10 between the plates 12 and 13. As the slide 22 descends, the plates 12 and 13 owing to their frictional engagement with the glove, begin their stripping action, any movement of the levers in excess of that necessary to clamp the plates 12 and 13 being taken up by the springs 17. As the cam rollers 24 move along the guide plates 46, the levers continue to swing inwardly enough to maintain the pressure upon the clamping plates as said plates follow the contour of the tip of the form 10 and slide off said form to clamp the glove directly and flat therebetween without wrinkles or creases. During the remainder of the descent of the rollers along the flat surfaces 45 of the cam plates 25, the glove remains clamped and the stripping is completed. Finally, during the

last part of such descent, the cam rollers move off the flat surfaces 45 and are spread apart or separated under the influence of the spring 23 to release the glove which drops on to the belt 31

5 and is conveyed out of the machine. On the ascent of the slide 22, the cam rollers are re-engaged with the surfaces 45 and finally slide off the guide plates 46 to be separated again by the spring 23 and to separate the clamping plates

10 ready to receive the next form therebetween.

It will be noted that the clamping plates are yieldably mounted and hence are self adjusting to compensate for variations in the dimensions of the work and of the parts, that being substantially flat they do not distort the garment gripped

15 between them, that the stripping action is performed by gripping one end portion of the garment and pulling longitudinally thereon in a manner which is most efficient, and that rolls, belts, gripping jaws and similar mechanisms are dispensed with to render the stripping mechanism positive and dependable in its action, regardless of whether or not the garment, such as a glove having a right hand or a left hand thumb, has 20 protruding parts or not.

25 Various changes may be made in the specific forms of the invention shown and described without departing from the spirit of the invention defined in the appended claims.

30 I claim:

1. In mechanism for stripping a garment from a form, a pair of levers, a slide pivotally supporting the levers, means for reciprocating the slide, a row of spring-pressed clamping plates on each 35 of the levers, a plate in the path of each of the levers to urge the levers toward each other, a second plate in the path of each lever and at one end of the adjustable plate to maintain the rows of clamping plates in pressed relation to each 40 other during a predetermined amount of the movement of the slide, said second plate being shaped to release the clamping plates at predetermined parts of said movement, and a conveyor belt below the second plate to receive a garment 45 stripped by the clamping plates and then released thereby.

2. In mechanism for stripping a garment from a form, a pair of levers, means for oscillating the levers toward and from each other, a row of 50 clamping plates each carried by one of the levers, each of the plates having a rod extending therefrom and slidably in one of the levers, a spring on each rod urging the plate thereon inwardly of the lever on which the plate is mounted, and 55 means for reciprocating the levers and the rows of plates thereon as a unit.

3. In mechanism for stripping a garment from a form, a pair of opposed rows of yieldable clamping and stripping plates, springs urging said rows toward each other in a direction to press the plates upon a garment and a form inserted therebetween, means for separating said rows sufficiently to permit the insertion therebetween of the form and the garment thereon and thereafter 60 moving the plates toward each other into direct pressed engagement with the garment, and means for reciprocating the plates during the engagement thereof with the garment, first to slide that part of the garment engaged thereby off the form 65 and thereafter to pull the remainder of the garment off the form.

4. In mechanism for stripping a garment off a form, a form, opposed spring-pressed rows of clamping members arranged to clamp the end 70 part of a garment and the form therebetween,

and means to move the members longitudinally off the form while the garment remains clamped thereby, first to slide the clamped part of the garment off the form and then to pull upon and move the clamped part of the garment in a direction to strip the garment off the form.

5. In mechanism for stripping a garment off a form, a pair of opposed oscillatory levers, a substantially vertical pivot for each lever, a row of yieldable clamping members on each lever opposed to the row on the other lever, each of the members having a flat clamping face, and means for substantially vertically reciprocating the levers.

6. A garment stripping mechanism according to claim 5 wherein the reciprocating means comprises a reciprocatory slide carrying the levers and a cam in the path of each of the levers.

7. In mechanism for stripping a garment from a form, a pair of opposed rows of spring-pressed clamping plates, means for reciprocating said rows and means for oscillating the rows to move said rows toward and from each other simultane-

ously during the reciprocation thereof comprising a fixed cam plate, a pair of spring pulled levers each carrying one of the rows of clamping plates, a cam roller on each of the levers and means for guiding the rollers on to and off the cam plate during predetermined parts of the reciprocatory movement of the rows.
